B. M. Johnson's
Design for Ornamenting Gas Fixtures
New York
Patented Sept 27 1859

Wes. 1150

B. M. Johnson, of New York, N. Y.
Letters Patent, No. 1150. Dated Sept. 27, 1859.

The schedule referred to in these Letters Patent and making part of the same.

To all whom it may concern:

Be it known that I, B. M. Johnson, of the City, County, & State of New York, have produced a new and original device for ornamenting cocks, couplings, brackets, and other parts of gas fixtures, Chandeliers &c. and I do hereby declare the following to be a full description of the same, reference being had to the accompanying drawings, - forming a part of this Specification, the same letters of reference wherever they occur referring to like parts.

Figure 1. is a side view of a gas cock, coupling of a gas pipe.

Letter a, is a vase like shaped socket into which the end of the gas pipe is inserted. Around the external edges of its mouth, is a subdivided rim b, having below it a marginal streak c, upon which rests the ends of six cross bars d, to form a series of lozenge shaped squares, across the face of the socket in the angles of which are scalloped out oval shaped devices e.

At the opposite edges of the vase or socket two leaf like ornaments f, having seven points each, and between which the vase is supported. These leaves are united at their base, by a band g, which joins the socket to the body of the cock h, the opposite faces of which are subdivided into lozenges, by a series of cross bars d, having at their angles, oval shaped scallops e, like on the faces of the socket, at the upper and lower edges of the axis of the cock h, are borders composed of a continuous succession of single pointed leaves i.

Letter j, is the tap of the cock, the thumb piece of which is flat, having at each edge a tulip shaped flower or leaf k, having seven points.

The base of this flower rests upon the stem l, of the tap, and supports between its points, a disk m, subdivided by lines into lozenges, having in their angles oval shaped scallops, in a like manner as before described on the faces of the cock. At the apex of the disk, is a shell like device n, supported on either side by scrolls p, the ends of which form a margin on the edges of the disk, till they meet the leaf k.

Letter q, is a band intervening between the cock h, and the coup-

ting or auxiliary cock σ . This cock is a duplicate of the cock τ , except that it has attached to its outer end a fleur d'lis like ornament, composed of a stem of four pointed leaves s , from the sides of which branch cornucopia s' , between which rise an oval shaped cloverlike bud s'' .

Letter t , is a tap or joint socket, having an axis through the cock τ . In the end of it is inserted a gas burner or pipe as may be desired. The sides of the tap are ornamented by the lozenge device, before described, -

Letter u , is a raised rim around the mouth of the joint socket. Resting upon this rim is a border of three pointed leaves v , which cover the end of the tap, around the base of which is a leaf like border w , resting upon a band x , which forms the axis of the tap; and around the upper edge of it is a bordering of drapery y , surrounding the base a^2 , of a fleur d'lis ornament b^2 , surmounting the tap, to complete the device for ornamenting cocks, couplings, brackets, and other parts of gas fixtures. Chandeliers.

Having now described my invention, I will proceed to set forth what I claim, and desire to secure by letters patent of the United States.

What I claim is the use of the devices hereinbefore described as adapted and used for ornamenting cocks, couplings, brackets and other parts of gas fixtures, and chandeliers, as set forth.

Witnessed,

C. L. Barrett.

Albert Smith.
